UNITED STATES PATENT OFFICE.

AMES T. BROWN, OF LEXINGTON, MASSACHUSETTS, ASSIGNOR TO INTERBORO MEDAL & BADGE MFG. CO., OF NEW YORK, N. Y., A FIRM COMPOSED OF CHARLES MANDELSTEIN AND JULIUS JURGENSEN.

DESIGN FOR A FINGER-RING OR SIMILAR ARTICLE OF JEWELRY.

52,467.

Specification for Design.

Patented Sept. 24, 1918.

Application filed April 16, 1918. Serial No. 228,977. Term of patent 7 years.

To all whom it may concern:

Be it known that I, AMES T. BROWN, a citizen of the United States, residing at Lexington, in the county of Middlesex and State of Massachusetts, have invented a new, original, and ornamental Design for a Finger-Ring or Similar Article of Jewelry, of which the following is a specification, reference being had to the accompanying drawing, forming a part thereof.

The drawing shows a perspective view of my design.

I claim:

The design for a finger ring or similar article of jewelry as shown.

In testimony whereof I hereunto affix my signature.

AMES T. BROWN.
